Inventor:

Henry A. Howe
by his Atty. S. J. Maguire

UNITED STATES PATENT OFFICE.

HENRY A. HOWE, OF ALBION, NEW YORK.

HARVESTER.

SPECIFICATION forming part of Letters Patent No. 298,854, dated May 20, 1884.

Application filed March 19, 1884. (No model.)

To all whom it may concern:

Be it known that I, HENRY ARCHIBALD HOWE, of Albion, in the county of Orleans and State of New York, have invented new and useful Improvements in Harvesters; and I hereby declare that the following is a full, clear, and exact description thereof, reference being had to the accompanying drawings, which form a part of this specification.

10 This invention relates to new and useful improvements in that class of harvesters in which the outer end of the platform, which is supported by the grain-wheel, may be raised or lowered from and to the ground, at the will of 15 the driver, by the operation of a lever attached near the inner end of the platform, within reach from the driver's seat; and the invention consists in the peculiar construction of the bracket which supports the platform, 20 its attachments, and the lifting mechanism, and also in the construction of the devices for supporting and adjusting the grain-wheel, all as shown, and hereinafter described and claimed.

25 In the drawings which accompany this specification, Figure 1 is a plan of a harvester of known construction with my improvement attached. Fig. 2 is a vertical central cross-section on line X X in Fig. 1. Fig. 3 is an elevation of the shoe to which the grain-wheel is adjustably secured. Fig. 4 is a cross-section of Fig. 3 on line y y. Fig. 5 is a perspective view of the inner end of the grain-platform, with the hand-lever for controlling the adjustment of the grain-wheel.

30 A is the harvester-platform; B, the grain-wheel; C, the shoe to which the grain-wheel of the platform is adjustably secured in the following manner: a a are parallel guides, 35 which hold the plate b in contact with the shoe and allow of its being freely moved up or down between the guides, and is limited in its downward adjustment by the stops a' d', cast integral, respectively, with the shoe C and plate b. d is the axle of the grain-wheel. It is cast integral with the plate b. A small roller, e, is secured to the lower edge of the shoe by means of ears c, which are cast integral therewith, and a chain, f, is attached to a

40 rod, g, which passes under the platform to the inner end thereof, and connects there with another piece of chain, h, which passes around

the roller i, and thence over the grooved quadrant k, where it is attached at l.

L is a bracket for connecting the table A 55 with the main frame by means of the extension s", which carries the standard m'. It consists of a base-plate, s, the outer end of which is provided with ribs s', which form a recess to receive the inner end of the platform 60 A, to which it is secured by bolts or in any convenient manner. Said bracket has cast integral therewith ears I, which support a roller, i. To the base-plate s is bolted the standard o, having on its upper end the segmental rack 65 p. n is a pin projecting from and forming an integral part of the standard o, on which is fulcrumed the hand-lever m, the lower end of which carries the quadrant k. p' is a spring-pawl engaging with the rack p, and is operated by the handle v.

In practice the driver is enabled to grasp from his seat the hand-lever m, and, by releasing the pawl from its engagement with the rack p, is at liberty to move the lever m either 75 backward or forward, the former movement effecting a raising and the latter a lowering of the platform at the grain-wheel. The lever m may be inclined toward the driver's seat, if necessary, to bring it within convenient reach, 80 or to allow the driver to exert his strength to more advantage.

It will be readily seen that with the controlling devices for the grain-wheel attached, as they are, to the platform itself, no disturbance of the adjustment can occur whether the platform is tilted or its distance from the ground changed at the inner end thereof. To prevent the rod g from forming a possible obstruction under the platform, and thereby get 85 disarranged, it may be held thereto in any convenient manner—for instance, by eyebolts or otherwise—and the grain-wheel B is prevented by proper stops, as a' d', from passing beyond its extreme limits of adjustment.

90 What I claim as my invention is—

1. In a harvester, in combination with the main frame and platform thereof, the bracket L, provided with ribs s' and the extension s", substantially as and for the purpose described. 100

2. The combination, in a harvester provided with means for adjusting the platform, of the bracket L, consisting of the plate s, ribs s', and ears I, cast in one piece, and constructed

to support the mechanism whereby said adjustment is accomplished, substantially as described.

3. The combination, in a harvester provided with means for adjusting the platform, of the bracket L, consisting of the plate s, ribs s', and ears I, cast in one piece, and provided with the standard o, secured to the base-plate s, and having cast integral therewith the rack 10 p and pin n, all constructed, arranged, and operating substantially as described.

4. In a harvester provided with means for adjusting the platform, in combination with the shoe C, having cast integral therewith the guides a a' and stop a', the plate b, having cast integral therewith the axle d and stop d', whereby the relative movement of the plate and guides is limited, substantially as described. 15

HENRY A. HOWE.
